UNITED STATES PATENT OFFICE.

CHARLES F. WRIGHT, OF AKRON, OHIO, ASSIGNOR TO THE DIAMOND MATCH COMPANY, OF CHICAGO, ILLINOIS, A CORPORATION OF ILLINOIS.

COVER-SUPPLYING MECHANISM FOR BOX-FILLING MACHINES.

Application filed April 22, 1926. Serial No. 103,673.

This invention relates to machines for filling boxes of the tray and shuck type, having reference to certain improvements in cover or shuck positioning mechanism for use especially in connection with the machine illustrated in Letters Patent of the United States No. 1,300,762, dated April 15, 1919.

The patented machine includes an endless conveyer for transporting complementary trays and shucks in endwise relation to each other, a guide-way for supporting a row of shucks laterally of the conveyer as it travels from one path to another, said guide-way having a delivery throat portion to receive the leading shuck, a friction element arranged in the throat portion in close relation to the conveyer, and a plunger head movable in the throat portion toward and from the conveyer, which head is operable in one active stroke thereof to move the leading shuck into engagement with the friction element and in another active stroke to move such shuck to the conveyer. Since the leading shuck of the row is positioned in the path of the plunger head by the end pressure of the succeeding shucks, there is liability of the telescoping and breaking of the contiguous edges of the shucks.

The object of my invention is to overcome the objection mentioned, and to that end the invention comprises various features of construction and combinations of parts which will be hereinafter described and claimed.

In the drawings—

Figure 1 is a side elevation, partly in section, of a match-box filling machine embodying a preferred form of my invention; the shuck positioning head being shown in its forward or inserting position.

Fig. 2 is a plan of the mechanism shown in Fig. 1.

Fig. 3 is a vertical section through the end of the machine, adjacent the shuck delivery mechanism, as on the line 3—3 of Fig. 2.

Fig. 4 is a horizontal section directly above the shuck delivery mechanism, as on the line 4—4 of Fig. 3.

Fig. 5 is a vertical section on a plane through the speed-roll bearings, as on the line 5—5 of Fig. 3.

Fig. 6 is a horizontal section on a plane immediately above the guide trough for the shucks, as on the line 6—6 of Fig. 5; the

shuck-positioning head being shown in retracted position to permit the forward movement of the leading shuck by the speed rolls.

Referring to the drawings, 10 designates a part of the main frame, and 11 designates a part of the main drive shaft of a box-filling machine. 12 designates a portion of a continuously driven tray-and-shuck conveyer the upper run of which travels along a bed or table 13 supported by the frame. 60 This conveyer preferably comprises a chain of links having outwardly projecting blade-like members 14, 15 which afford a succession of aligning holders for complementary trays and shucks. This conveyer passes 65 about suitably located sprocket wheels at the respective ends of the bed, one of which wheels is shown at 16. Located at one side of the path of the upper run of the carrier, and at a right angle thereto, is a trough 17 70 adapted to contain a row of trays which are fed toward and successively entered in the adjacent tray holders of the conveyer. At the end of the conveyer, adjacent the sprocket wheel 16, is a trough 18 adapted to 75 contain a row of box shucks or covers (a) which are successively entered by means of a reciprocating head 19 in the succeeding shuck receptacles of the conveyer as the latter travels from its lower to its upper path, 80 the relation of the tray and shuck inserting means being such that complementary trays and shucks are inserted in and supported by the conveyer and the trays are carried thereby beneath a suitably-located match supply 85 hopper 20.

Excepting as hereinafter particularly described the foregoing mechanism is or may be of the character illustrated in Patent No. 1,300,762 aforesaid.

The shuck trough 18 is supported adjacent the path of the blades 15 and in substantial horizontal alignment with the axis of the wheel 16, the width of the trough being such that the shucks are guided, end to end, with one of the long narrow sides of each shuck supported on a conveyer 21 which extends along the bottom of the trough. The conveyer 21 is preferably in the form of a chain which passes about suitable sprocket wheels located adjacent the respective ends of the trough, the wheel 22 at the delivery end of the trough being fast on the main shaft 11 of the machine so as to impel the conveyer 21 together with the 105 110

shucks, along the trough. The delivery end of the shuck trough terminates in advance of a throat element which leads to the path of the shuck holders of the conveyer, which throat element comprises a shelf afforded by the depending angular portion 23 of a bar 24 bolted to the underside of the supporting bed 13 and the overhang end portion 23' of a depending bar which is affixed to a bracket 10 24' on the table 13.

Mounted at the delivery end of the shuck trough are upper and lower transverse rolls 25 which are driven in opposite directions at high speed, and are so relatively disposed as 15 to grip the forward end of the leading shuck and transfer it rapidly to the shelf and against the vertical member 26 of the latter, which member thus acts as a stop or abutment for the shuck. In the present instance 20 these speed rolls are fast on spindles 27 journaled in elongated bearings 28 projecting from an adjustably-mounted bracket 29 at the end of the main frame; the two spindles being connected by intermeshing gears 30, 25 and the lower spindle being provided with a sprocket wheel 31 which is connected by means of a chain 32 with a sprocket wheel 33 on the main shaft.

The instant a shuck is positioned on the 30 shelf by the rapidly rotating rolls 25, such shuck is bodily entered in the opposing shuck holder of the conveyer 12 by the impact against the side of the shuck of the reciprocating head 19. This head is formed on the 35 upper end of a lever 34 which is fulcrumed at its lower end on a stud 35 supported in a bracket 36 on the main frame. The lever has a laterally-projecting roll 37 which is held yieldingly against the face of a rotating cam 38 by means of a suitably-disposed spring 39, which cam is fast on the main shaft and is of appropriate form to effect 40 and permit the timed movements of the lever. The upper portion of the lever 34 is 45 provided adjacent the head 19 with a laterally projecting rib 40 which, by actuation of the lever, is reciprocated across the front or delivery end of the shuck trough.

The timed relation of the mechanism just 50 described is such that as the shucks are advanced along the trough 18 the leading shuck comes in contact with the opposing rib 40 and the latter thus acts as a stop to arrest the movement of the shucks until the head 55 19 has reached the limit of its outward travel, as seen in Fig. 6. Thereupon, the row of shucks is advanced by the conveyer 21 until the forward end of the leading shuck is engaged by the rolls 25 which rolls by virtue of their rapid rotation instantly advance 60 the leading shuck until it comes in contact with the stop 26, thus well separating such shuck from the remainder of the row. The lever 34 is then actuated by the spring 39 to 65 swing the head forward and push the oppos-

ing shuck into the conveyer. As the head advances, the rib 40 passes in front of the shuck trough and halts the row of shucks until the head has positioned the shuck in the conveyer 12 and has returned to its outer position in readiness to engage the next succeeding shuck, and so on.

Since the surface speed of the constantly driven rolls 25 is in excess of that of the feed conveyer 21 and the row of shucks 70 thereon, the plunger head 19 has time to move sufficiently forward to insure the obstruction of the path of the shucks at the delivery end of the trough 18 by the stop rib 40 before the leading shuck is engaged by the 75 rolls, thereby holding back the row of shucks contained in the trough, and obviating any liability of the telescoping and the breaking of the edges of the shucks while the separated shuck is being pushed into the conveyer 12 by the plunger head. Hence, a 80 more rapid and efficient delivery of the shucks to the conveyer 12 is accomplished than in the previous construction referred to 85 wherein the leading shuck is pushed to a position in front of the plunger head by the direct action of the train of shucks contained in the trough.

It is to be understood that my invention is 90 not limited to the particular construction 95 herein disclosed, as the mechanism may be modified within the principle of the invention and the scope of the appended claims.

I claim—

1. The combination with a travelling conveyer having a succession of shuck holders, of a guide-way for a row of box shucks, means for moving the shucks along the guide-way, a shuck-supporting member adjacent the conveyer, rapidly rotating rolls for 100 engaging each succeeding leading shuck of the row, separating it from the row and transferring it to the said supporting member, and means for moving the shuck from the supporting member, to a holder of the 105 conveyer.

2. The combination with a travelling conveyer having a succession of shuck holders, of a guide-way for a row of box shucks, means for moving the shucks along the 110 guide-way, a shuck-supporting member adjacent the conveyer, means for engaging each succeeding leading shuck of the row and transferring it with increased speed to the said supporting member, and a reciprocating element for moving the shuck from the supporting member to a holder of the 115 conveyer, said element having a stop portion movable into and from the path of the shuck before its engagement by the 120 said supporting member, and a reciprocating element for moving the shuck from the supporting member to a holder of the conveyer, said element having a stop portion movable into and from the path of the shuck before its engagement by the 125 said supporting member.

3. The combination with a travelling conveyer having a succession of shuck holders, of a guide-way for a row of box shucks, means for moving the shucks along the 130

guide-way, a shuck-supporting member adjacent the conveyer, rapidly rotating rolls for engaging each succeeding leading shuck of the row, separating it from the row and transferring it to the said supporting member, and a reciprocating element for moving the shuck from the supporting member to a holder of the conveyer, said element having a

stop portion movable into and from the path of the shuck before its engagement by the 10 said rolls.

Signed at Barberton in the county of Summit and State of Ohio this 14 day of April, A. D. 1926.

CHARLES F. WRIGHT.
